UNITED STATES PATENT OFFICE

2,426,679

CIGARETTE BOX

William S. Groom, Fort Mitchell, Ky.

Application January 25, 1945, Serial No. 574,475

1 Claim. (Cl. 206—1)

1

This invention relates to improvements in receptacles and is particularly directed to a box for containing perishable articles such as cigarettes, or the like.

An object of the invention is to provide a box for perishable articles having improved structural features which offer unobstructed accessibility to the box receptacle and which upon end for end rotation of the box case has structure which cooperates with the flat supporting surface of the box to provide an airtight and dust-proof compartment for the articles in the receptacle.

Another object of the invention is to provide improved features for a case and a pivoted receptacle therefor which precludes excessive rocking movement of the receptacle and serves to maintain said receptacle in a horizontal position regardless of the character of the rotational movement of the case about the pivotal axis, and which is especially useful when the receptacle is in its accessible position so that articles may be easily grasped and removed therefrom.

A further object of the invention is to provide a cigarette box which offers exterior surfaces for decorative purposes in its closed, inverted position and which presents its contents for ready accessibility in its open position.

Other objects will be apparent from the following specification and drawings, in which:

Fig. 1 is a perspective view of my cigarette box in position for ready access to the contents thereof.

Fig. 2 is a fragmental, perspective view of my box in closed position.

Fig. 3 is an enlarged, cross-sectional view taken through the transverse center of the box illustrated in Fig. 1.

Fig. 4 is an enlarged, cross-sectional view taken through the longitudinal center of the box shown in Fig. 1.

Fig. 5 is a cross-sectional view taken through the transverse center of the box illustrated in Fig. 2, the dotted lines illustrating an intermediate, operative position of the box.

The embodiment of my invention consists of a cigarette box 8 comprising an outer case 9, having side walls 10 and 11, end walls 12 and 13, and an interconnected bottom 14. As illustrated in Figs. 1, 3 and 4, the bottom 14 of the outer case normally rests upon a flat supporting surface 15 so that an opposed open side 16 is in an upturned position for ready access to the interior of the case.

An open topped receptacle 17 is disposed within

2

the case and consists of flat end walls 18 and 19 and side walls 20 and 21 having their outer surfaces transversely curved as is indicated by the reference numeral 22. The receptacle has a bottom 23 which is connected to the lower ends of the walls and upon which cigarettes 24 or other perishable articles may rest.

The receptacle is maintained in substantially horizontal position regardless of the rotational movement of the case by means of pivot pins 25 and 26 which are respectively anchored in and extend horizontally from the side walls 12 and 13 and freely engage bearings 27 and 28 anchored in the side walls 18 and 19 respectively of the receptacle (Fig. 4). These pivot pins are in axial alignment and are disposed parallel to the longitudinal dimensions of the case and the receptacle. As most clearly illustrated in Fig. 3, the pins are also located at the transverse centers of the receptacle side walls and are also disposed above the center of gravity of the receptacle by mounting a weighted plate 29 beneath the bottom 23 of the receptacle by means of nails 30, or the like.

It will be noted that the open topped receptacle 17 is pivotally mounted within the case adjacent the open side 16 so that the faces of the openings in the case and the receptacle are disposed in offset, parallel planes. This position of the receptacle within the case protects it from accidental contact with moving objects, or the like to preclude rocking or tipping of the receptacle and the receptacle is also mounted near, or adjacent to the open side of the case to permit ready access to the contents therein.

To form a closed compartment for the receptacle, the case 9 is manually rotated in a transverse plane of the pivotal axis between the case and the receptacle, as is indicated by arrows in Fig. 3. When this rotation has been manually carried through 180°, the open top assumes a position to rest upon the supporting surface 15. The flat surface therefore seals off the opening 16 in the case and cuts off the entrance of air and foreign materials into the compartment. The closed position of the case is illustrated in Figs. 2 and 5, and it will be noted that the exterior, uninterrupted surfaces of the case are particularly adaptable for decorative purposes.

What is claimed, is:

A cigarette box comprising a hollow, manually rotatable closure member having side walls, end walls, a bottom, and a normally upturned open side opposed to said bottom, a shallow pendulous cigarette container disposed within the

closure member and having side walls, flat end walls, a bottom wall, and an open top opposed to said bottom wall, the edges of said open sides being normally positioned in offset parallel planes with the container in accessible position, axially aligned, closed journal bearings between adjacent side walls of the container and closure member, the axis of said bearings being disposed parallel to the common longitudinal dimension of the closure member and the container and located at the transverse center of the container side walls and above the center of gravity of said container, said journal bearings being spaced inwardly from the edge of the open side of the closure member a distance at least equal to the distance between the journal bearing and the bottom of said container, whereby upon manual rotation

of the closure member about the longitudinal dimension, said closure member revolves around the container and the open side of the member forms with the box supporting surface a closed compartment for said container.
